Attorneys

UNITED STATES PATENT OFFICE.

HENRY D. HUGHES, OF DALLAS, TEXAS.

COUNTERFLOW CONDENSER.

Application filed June 10, 1926. Serial No. 114,956.

This invention relates to new and useful improvements in a counter flow condenser.

One object of the invention is to provide an apparatus of the character described for condensing vapors and whereby a cooling fluid may be readily supplied to the condenser coils.

Another object of the invention is to provide an apparatus of the character described whereby a cooling fluid may be applied for condensing vapors, said cooling fluid and vapors being circulated, one through condenser coils and the other about said coils.

A further feature of the invention is to provide an apparatus of the character described whereby the velocity of the flow of either the vapor to be condensed or the cooling fluid may be varied to effect the necessary heat exchange to accomplish the desired result.

With the above and other objects in view this invention has particular relation to certain novel features of construction, operation and arrangement of parts, an example of which is given in this specification, and illustrated in the accompanying drawings, wherein:—

Figure 1 shows a plan view of the device, showing the cover removed, and

Figure 2 shows a vertical sectional view thereof.

Referring now more particularly to the drawings, wherein like numerals of reference designate similar parts in each of the figures the numeral 1 designates an enclosed box-like casing, having the end compartments 2, 2, formed therein by the solid end partitions 3, 3, leaving return bends exposed, or the horizontal baffles can be extended through to each end of box.

There are the inlet and outlet manifolds 4 and 5 in the respective compartments 2, and a series of coils 6 connect these manifolds. As shown the respective coils of this series are disposed in parallel vertical planes, but if desired they may be arranged in horizontal planes, or may be worm type coils.

Spaced apart between the end partitions 3, 3, and extending from top to bottom of the casing are the vertically disposed baffles 7 arranged in staggered relation. These baffles are secured to the respective sides of the casing 1 with their alternating free ends falling short of the opposite wall to provide the ports, or passageways 8, around said free ends. The respective turns of the coils pass

through these baffles and form fluid tight joints therewith, if desired.

Spaced apart between the top and bottom of the casing 1 and extending from side to side thereof are the horizontal partitions 9, also arranged in staggered relation and secured to the respective vertical end partitions 3, 3. These partitions are disposed between the turns of the coils 6 and their alternating free ends fall short of the opposing partition 3 to provide the ports or passageways 10 around their free ends.

The cooling fluid may be introduced into the bottom of the casing at one end through the inlet pipe 11 and will flow transversely back and forth in a general zigzag course beneath the lower partition 9, between the baffles 7 to the other end of the casing and then will rise to the next level and continue to flow transversely back and forth ascending from level to level as it passes around the free ends of the partitions 9 and finally is discharged from the top of the casing through the outlet 12. This cooling fluid passing around the coils will cause a rapid condensation within the coils. The top of the casing may be open, if desired, but will preferably be closed, and if closed the velocity of the cooling fluid may be varied to obtain the desired results.

It is also possible to circulate the cooling fluid through the coils with the vapor to be condensed, circulating around them and in such case the condensation will form on the coils and drop back into the casing and may be drawn off in any obvious manner desired.

What I claim is:—

1. A counter flow condenser including an enclosed casing, manifolds within the casing, one located at each end thereof, a series of coils connected into said manifolds, the coils being disposed in parallel planes, end partitions extending from side to side and from top to bottom of the casing and spaced inwardly from the respective ends of the casing, spaced partitions extending from the top to bottom of the casing forming baffles disposed in staggered relation, said baffles being secured to the respective sides of the casing with their alternating free ends falling short of the opposite wall to provide a passage around said free ends, the respective turns of the coils passing through the end partitions and baffles and forming fluid tight joints therewith, horizontal partitions spaced apart between the top and bottom of the cas-

ing and extending from side to side thereof, arranged in staggered relation, and secured to the respective vertical baffles said horizontal partitions being disposed between the 5 turns of the coils and their alternating free ends falling short of the opposing end partitions to provide passageways around their free ends, an inlet in the bottom of the casing at one end and an outlet leading from the top 10 of the casing at the other end.

2. A counter flow condenser including an inclosed casing, partitions across the casing spaced from the ends thereof to form end compartments, a manifold in each compartment 15 and a series of coils connecting said manifolds, the coils being disposed in parallel planes, baffles spaced apart between the

partitions and disposed in parallel planes, said baffles being secured to the respective sides of the casing with their alternating free 20 ends falling short of the opposing side of the casing forming a passage around said free ends, horizontal partitions spaced apart with the free ends of said horizontal partitions falling short of the opposing transverse end 25 partitions providing a passageway around said free ends of said horizontal partitions, an inlet entering the casing bottom near one end thereof and an outlet leading from the top of the casing near the other end thereof. 30

In testimony whereof I have signed my name to this specification.

HENRY D. HUGHES.
